DENTURE CLAMP

Charles Haller, Denver, Colo.

Application August 26, 1943, Serial No. 500,151

5 Claims.

(Cl. 32—19)

This invention relates to holding or clamping means employable in connection with prosthetic dentures, and more particularly to removable and replaceable means adapted to engage at times with a dental plate or appliance as positioned for use and hold said plate or appliance against displacement.

A further object of the invention is to provide a simple, conveniently removable and replaceable clamp primarily adapted for engagement with a lower dental plate or appliance to yieldably but securely hold said plate or appliance in the desired seated relation with the jaw of a user during eating operations.

A further object of the invention is to provide a denture clamp of the character described adapted for instant installation or removal relative to a dental plate or appliance without the use of tools.

A further object of the invention is to provide a denture clamp of the character described that presents a minimum of discomfort to the user and little interference with normal muscular and dental functions when in use.

A further object of the invention is to provide a denture clamp of the character described that is simple and inexpensive of manufacture, susceptible of convenient cleaning and sterilization, readily adjustable to exactly fit the requirements of a specific user, durable, and which is positive and efficient in accomplishing the purposes for which designed.

My invention consists in the construction, arrangement, and combination of elements hereinafter set forth, pointed out in my claims, and illustrated by the accompanying drawing, in which—

Figure 1 is a front elevation of a preferred form of the improved clamp as constructed and assembled ready for use. Figure 2 is a cross-section taken on the indicated line 2—2 of Figure 1. Figure 3 is a longitudinal section taken on the indicated line 3—3 of Figure 2. Figure 4 is an elevation, on a somewhat reduced scale, showing the device of Figure 1 as positioned for actual use, the tooth elements of the appliance engaged by the clamp being illustrated in full lines, and the relative position of the user's head being indicated by broken lines.

In the construction of the improvement as shown, the numeral 10 designates, generally, a frame member whereon the other elements of the device are mounted in operative association. The frame member 10 may be variously constructed and arranged to provide the elements

essential to its function, and is shown as an integral, rigid unit pressed or moulded to the desired form from any suitable material, such as synthetic resins, plastics of various types, lightweight metals and alloys, and the like. As will

5 be apparent from the following detail description of the functions and relationships of the elements comprised in the frame member 10, said member may, if desired, be constructed otherwise than by pressing or moulding and may take the form of an assembly of rigidly-interconnected, separate elements. Whatever be its specific construction, the frame member 10 includes a rigid, substantially straight bar portion 11, desirably contoured in its midportion to engage beneath and bear comfortably upwardly against the chin of a user, of a length sufficient to provide like, oppositely-directed end portions 12 extending beyond the jaws of the user. Spaced webs 13 are formed with or are fixed to the midportion of the bar 11 and depend from the under surface of said bar in longitudinally-disposed, parallel relation to define a downwardly-opening slot disposed in longitudinal alignment with said bar. The webs 13 serve to brace, strengthen and stiffen the bar 11 as well as to provide a mounting for other elements of the device.

Like pins 14 engage, preferably removably, in spaced parallelism through the webs 13 in intersecting relation with the slot defined by said webs, said pins being similarly spaced below the adjacent under side of the bar 11 and like distances from the transverse center line of said bar, and said pins serve to mount and position a pair of hairpin type spring elements, each of which has an intermediate portion coiled about a pin 14 within the slot defined by the webs 13, a terminal portion 15 directed outwardly of said slot in bearing relation with the under side of the bar 11, and a spring arm 16 directed at an acute angle with the portion 15 to extend outwardly and downwardly from between the webs 13 for termination in a knobbed or otherwise enlarged end well beyond the associated web margins and in spaced, underlying relation with the corresponding bar end portion 12. As will be apparent, the spring elements are so coiled about their respective pins 14 as to tension their spring arms 16 to yieldably resist displacement towards the corresponding bar ends 12.

Each of the bar end portions 12 is intersected by an enlarged hole 17 through each of which is loosely and slidably received the shaft of a pull-rod 18 which slidably engages at its lower end,

as by means of an eye 19 formed on said end of the pull-rod, with the adjacent spring arm 16 and is prevented from separation from said arm by the knob or enlargement terminating the latter. The upper extension of each pull-rod 18 is bent at substantially a right angle with its shaft to form an arm 20 substantially coplanar with and approximately paralleling the associated spring arm 16, and the free end of said arm 20 is flattened, or otherwise reduced in thickness, as indicated at 21, and terminates in a relatively-short, downwardly-curved hook 22, so that the free end of the arm 20 may engage with its portion of reduced thickness in a groove or clearance provided for such purpose between adjacent teeth 23 of a dental plate or appliance 24 when and as positioned for use on the lower jaw of a user, the hook 22 engaging inner surfaces of the teeth or appliance structure to prevent outward longitudinal retraction of the arm 20 from its engaged relation.

Functioning of the device for the purpose of holding dental appliances or plates in position and against displacement during eating operations should be obvious from the showing and foregoing description. With an appliance in place on the lower jaw of a wearer, the bar 11 is positioned beneath the user's chin, the pull-rods 18 moved upwardly against the resisting tension of their respectively-engaged spring arms 16, the arms 20 entered through the corners of the mouth to engagement of their hooked ends between the teeth 23, and the pull-rods then released to permit the action of the spring arms 16 to be transmitted through said pull-rods and their arms 20 to yieldingly but firmly hold the denture in place. Upper surfaces of the arms 20 are recessed in the notches or grooves provided so that they are below the adjacent tooth surfaces, and the enlarged holes 17 permit such motion of the pull-rod shafts as may be necessary to fit the device comfortably to the lips and chin of the user.

Since many changes, modifications and variations in the specific form, construction and arrangement of the elements shown and described may be had without departing from the spirit of my invention, I wish to be understood as being limited solely by the scope of the appended claims, rather than by any details of the illustrative showing and foregoing description.

I claim as my invention:

1. A denture clamp of the character described, comprising a frame member engageable beneath the chin of a user, hooked rods slidably mounted through opposite ends of said frame member for engagement of their hooked upper ends with a lower dental appliance, and spring means engaging between said rods and frame member to yieldingly urge the hooked ends of said rods towards the frame member.

2. A denture clamp of the character described, comprising a bar-like frame member engageable beneath the chin of a user and adapted to extend at each end beyond the jaws of the user, rods 5 loosely and freely slidable through the ends of said frame member, inwardly-directed hooks on the upper ends of said rods engageable with opposite sides of a lower dental appliance, and resiliently-yieldable means engaging between said rods and frame member to urge the hooked ends of the former towards the latter.

3. A denture clamp of the character described, comprising a bar-like frame member adapted for engagement beneath the chin of a user with its 15 ends projecting beyond the user's jaws, a hole intersecting each end of said frame member, a shaft loosely and slidably received in each of said holes, a hook on the upper end of each of said shafts inwardly overhanging said frame member for engagement with an adjacent portion of a lower dental appliance, and spring means carried by and beneath said frame member in slidable engagement with lower ends of said shafts to yieldingly urge the hooked ends of said shafts towards said frame member.

4. A denture clamp of the character described, comprising a bar-like frame member adapted to engage beneath and project at each end beyond the chin of a user, shafts loosely and slidably engaging through the projecting ends of said frame member, inwardly-directed, hooked arms on the upper ends of said shafts engageable with opposite sides of a lower dental appliance, spaced webs depending from the under side of said frame member to define a downward and endwise opening slot longitudinally beneath said member, pins 30 removably intersecting said slot, and a spring carried by each of said pins in slidable engagement with the lower end of an adjacent shaft to yieldingly urge the hooked end of the latter towards said frame member.

5. In a device of the character described, a frame member comprising a substantially straight, bar-like portion adapted to engage beneath and project at each end beyond the chin of a user and spaced, parallel webs depending from the central under side of said bar-like portion to define a slot longitudinally of and opening downwardly from the frame member, shafts loosely and slidably engaging through relatively enlarged holes in the projecting ends of the frame member, angularly-related, inwardly-extending arms on the upper ends of said shafts, hooks on the inner ends of said arms engageable at times 45 with opposite sides of a lower dental appliance, and resiliently-yieldable means operatively mounted in and extending beyond the slot between said webs in slidable engagement with lower ends of said shafts to urge the hooked arms of the latter towards said frame member.

CHARLES HALLER.
